US0D1002640S

(12) **United States Design Patent** (10) Patent No.: **US D1,002,640 S**
(45) Date of Patent: ** Oct. 24, 2023

(54) **DISPLAY SCREEN OR PORTION THEREOF
WITH GRAPHICAL USER INTERFACE**

- (71) Applicant: **Apple Inc.**, Cupertino, CA (US)
- (72) Inventors: **Teofila Connor**, San Francisco, CA (US); **Allison W. Dryer**, San Francisco, CA (US); **Cas G. Lemmens**, San Francisco, CA (US); **Marcel van Os**, Santa Cruz, CA (US)
- (73) Assignee: **Apple Inc.**, Cupertino, CA (US)
- (**) Term: **15 Years**
- (21) Appl. No.: **29/882,376**
- (22) Filed: **Jan. 13, 2023**

Related U.S. Application Data

- (63) Continuation of application No. 29/803,618, filed on Aug. 13, 2021, now Pat. No. Des. 975,722, which is a continuation of application No. 29/737,008, filed on Jun. 4, 2020, now Pat. No. Des. 928,200, which is a continuation of application No. 29/682,307, filed on Mar. 4, 2019, now Pat. No. Des. 886,844, which is a continuation of application No. 29/606,386, filed on Jun. 4, 2017, now Pat. No. Des. 842,333.

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The outermost broken lines in the FIGURE show a display screen or portion thereof, and form no part of the claimed design. The other broken lines in the FIGURE show portions of the graphical user interface that form no part of the claimed design.

1 Claim, 1 Drawing Sheet
